CHAMPAGNE BUCKET

Walter S. Taylor, Hammondsport, N.Y. 14840

Filed Jan. 7, 1965, Ser. No. 83,316

Term of patent 14 years

(Cl. D44—15)

FIG. 1 is a perspective view of a champagne bucket showing my new design;

FIG. 2 is a vertical sectional view thereof;

FIG. 3 is a top plan view with the cover removed for convenience of illustration;

FIG. 4 is a sectional view on line 4—4 of FIG. 2.

I claim:

The ornamental design for a champagne bucket, as shown and described.
